WALL-MOUNTED COMBUSTION SPACE
HEATER WITH WINDOW-ACCOMMO-
DATED AIR DUCT AND FLUEMarc Resek, Cleveland Heights, Ohio, assignor
to Perfection Stove Company, Cleveland, Ohio,
a corporation of Ohio

Application January 24, 1947, Serial No. 723,926

13 Claims. (Cl. 126—110)

1

This invention, generally, is in the class of stationary space heaters; and it consists of a heater of this class that is similar in some respects to so-called wall furnaces in that it is intended to be attached to a wall of a building, and while herein disclosed as incorporating a gas burner, it will be understood that the invention embraces in its scope any suitable kind of combustion device.

It is the fundamental purpose of my invention to provide a space heater incorporating a combustion device for installation on a wall adjacent to or under a window and that has a flue for carrying off the products of combustion and a duct for supplying fresh air to support combustion, which flue and duct are arranged to project out through the window between a part of the window frame and sash, preferably between the window sill and the bottom of the lower sash, thereby to minimize the trouble and expense of installation, and to avoid the necessity for making a flue opening in the wall of the building.

A further object of the invention is to enclose said flue within the duct in spaced relation to the walls thereof so as to insulate the surrounding window parts from the heat of the products of combustion.

Other objects are to provide a space heater of the aforesaid character that is highly efficient; that is simple and relatively inexpensive of construction; that is neat and attractive in appearance and wherein the top of the housing is insulated and provides a ledge in front of the window; wherein the aforesaid duct is shaped to embrace the window ledge so that it aids in holding the heater in proper relation to the wall and so that the sash interfits with the top of the duct in such manner as to effectively close the joint between the sash and duct, and to provide a heater of the character above set forth which is thoroughly safe from the standpoints of fire hazard and asphyxiation, and wherein the draft is not adversely affected by changes in air pressure and by the winds.

A further object is to provide a construction that readily lends itself to forced draft circulation and in which the incorporation of air impelling means for such purpose is convenient and optional.

In the accompanying drawing, wherein like reference characters designate like parts in the two views, Fig. 1 represents a front elevation, partly in section, of a space heater embodying my invention and showing the same mounted on the wall of a building in association with a window; Fig. 2 is a vertical section through the heater and adjacent portions of the wall and window with the burner and air impelling means shown in elevation; Fig. 3 is a horizontal section on the line 3—3 of Fig. 2, and Fig. 4 is a fragmentary perspective view of the heater.

2

The heater includes a housing designated, generally, by the reference numeral 1. This housing has a duct 2 that extends from its rear side adjacent the top thereof. An interior structure or casing, generally designated 3, has a flue 4 that projects rearwardly from its upper end through and beyond the duct 2. The housing 1 is constructed of sheet metal and comprises a front wall 10, a rear wall 11, end walls 12 and 13, and a double, insulated top wall 15 of which the corresponding wall of the duct 2 constitutes an extension.

The interior structure or casing 3 is made up of a front wall 20, a rear wall 21, top and bottom walls 22 and 23, respectively, and end walls 24. The latter walls depend from the ends of the top wall 22 a suitable distance and terminate at their lower ends in outwardly inclined portions 25 that join the end walls 12 and 13 of the housing, the latter walls being provided with openings 26 immediately above said portions 25. A wall extension or partition 27 extends across the top of the casing 3 and down the ends thereof in the plane of the back wall 21, the side portions of said extension or partition fitting the inclined portions 25 of the end walls 24. Thus, a vertical passage is set off, separate from the air circulating space of the heater, through which outside air is supplied to the bottom of the combustion chamber, as will heretinafter more fully appear. The rear wall 21 of the casing 3, below the aforesaid inclined portions 25, extends to the end walls of the housing, but stops short of the bottom wall 23 so as to provide an air passage therebeneath. The bottom wall 23 is extended rearwardly beyond the vertical plane of the wall 21 and joins the lower edge of the rear wall 11 of the housing. The beforementioned flue 4 is of a width equal to the distance between the end walls 24 and is positioned in the duct 2 in spaced relation to all walls thereof, suitable means (not shown) being employed for maintaining the walls of the flue in properly spaced relation to the walls of the duct. Shown as applied to the inner and outer surfaces of the front wall 20 and the top wall 22 of the interior casing 3 are heat transfer fins 30.

Situated within a combustion chamber C, enclosed by the casing 3, is a combustion device 35, shown as a gas burner incorporating a mixing tube 36. Gas is supplied to the mixing tube of the burner through a pipe 37 equipped with a valve 38 by which the gas may be turned off and on. Also included in the gas supply connections, as herein disclosed, are a pressure regulator 40 and an automatic control means 41, the latter being of usual character and serving to regulate the flow of gas according to temperature requirements. A pilot burner 45, arranged in lighting relation to the burner 35, is formed by a tube that

joins the gas supply pipe 37 ahead of the valve 38 through a cock 41.

Incorporated in the bottom of the housing, below the interior casing 3, and serving to support the latter, are brackets 50 that are adapted to be fastened to a wall W of a building or, more accurately, to the base board w' thereof (according to the present installation) with the duct 2 of the housing projecting through a window in said wall, the frame whereof is designated F. A portion of the bottom wall of said duct 2, remote from the housing, is depressed to provide a shoulder 51 that overhangs the window ledge L, thereby to assist in holding the heater in proper relation to the wall and window; and the rear edge portion of the top wall 50 is depressed and shaped to receive the lower edge of the window sash S, thereby to effectively close the joint between the sash and the heater throughout the width of the latter. As appears from Fig. 1, the heater is somewhat narrower than the window and is arranged centrally thereof, and the parts of the opening between the sash and window sill, beyond the ends of the heater, are occupied by closure means 55.

The pilot burner 45 may be lit when the cock 41 is opened by projecting a match through aligned holes 56 in the adjacent end walls of the housing and casing. Now, by opening the valve 38, gas is supplied to the burner 35 under control of the pressure regulator 40 and automatic control means 41 and is ignited from the pilot burner. The products of combustion from the burner are led to the outside of the building through the flue 4 while fresh air enters through the surrounding portion of the duct 2 and passes downwardly through the vertical passage between the rear wall 21 of the casing and the corresponding wall 11 of the housing and to the rear of the wall extension or partition 27 and enters beneath the wall 21 into the bottom of the space occupied by the burner, thereby to furnish primary air through the mixing tube 36 and secondary air directly to the flame of the burner. The fact that the combustion air is warmed as it enters by heat from the flue and combustion chamber wall, increases the efficiency of the burner. Heat is also transmitted from the combustion chamber through the walls 20 and 22 to the circulating space between the front and top walls of the housing and casing, such transmission of heat being enhanced by the heat transfer fins 30. The heated air is discharged from the circulating space into the room through an opening 57 that extends along the front of the housing adjacent the top thereof, while cool air enters said circulating space through the open bottom of the housing. Obviously, the outlet and/or inlet openings of the circulating space may be covered by grills, or said openings may consist of ornamental perforations in the walls of the housing.

To increase the movement of air through the circulating space, air impelling means may be incorporated in the heater, such being illustrated in the present embodiment as a fan 60 that is driven by an electric motor 61 shown as supported by a frame structure 62 in the lower portion of the housing. In any event, a thermosiphon circulation of air prevails through the passages between the end walls of the casing and housing, and to which passages air is admitted through the openings 26.

Thus it will be seen that my invention provides a very efficient space heater of the circulating type, and incorporating a combustion device, that

may be easily and quickly installed on a wall in connection with a window, and in which the combustion chamber and flue are effectively insulated by the disposition of the cool air ducts and passages thereby to prevent radiation or transmission of intense heat from the interior structure to the adjacent or surrounding wall and window parts. Insulation of the top wall 15 permits it to be used as a support for general purposes.

Extension of the outlet end of the flue 4 beyond the inlet end of the duct 2, as shown in Fig. 2, insures against contamination of the air that is supplied to the burner through said duct, by the products of combustion escaping from the flue. However, by disposing the inlet of the duct and the outlet of the flue in proximity to each other, particularly as illustrated, air pressure is equalized between said inlet and outlet regardless of wind intensity or direction. It is evident, therefore, that difficulties encountered in combustion devices wherein the air inlet and flue outlet are distantly separated or remote from each other, and which difficulties are caused by atmospheric conditions—that is to say, by changes in air pressure and by the wind—are obviated in my improved arrangement.

Obviously, as a manufacturing expedient, the partition 27 may consist of the top and side marginal portions of a sheet of metal that forms, also, the rear wall 21 of the interior structure or casing 3.

Having thus described my invention, what I claim is:

1. A space heater for installation on the inner side of a building wall below a window, said heater comprising a housing including top, front and rear walls, and end walls that are joined to the lateral edges of the former walls, a duct extending rearwardly from the top of the housing and opening into the housing through said rear wall, an interior structure including front, rear and top walls that are spaced from the corresponding walls of the housing, a bottom wall for the interior structure extending from the lower end of the front wall thereof to the bottom of the rear wall of the housing, a passage being provided between the rear walls of said structure and housing that communicates at its upper end with the aforesaid duct, a partition shutting off communication of said duct with the space between the top walls of said structure and housing, the rear wall of the structure being formed to provide communication between the bottom portion of said passage and the corresponding portion of the interior of the housing, end walls for the structure that depend from the top wall thereof and terminate at a point intermediate the top and bottom walls of the structure where they are deflected outwardly and join the end walls of the housing, the end walls of the housing having air admitting openings that lead into the lower portions of passageways between the end walls of the structure and housing, the aforesaid partition including depending portions that separate said passageways from the previously mentioned passage, a combustion device within the interior structure, and a flue leading from the top portion of said interior structure.

2. A space heater comprising the combination of elements defined by claim 1, and heat transfer fins projecting from the outer surfaces of the top and front walls of the interior structure.

3. A space heater comprising the combination

of elements defined by claim 2, and air impelling means supported within the lower portion of the housing and arranged to move air upwardly through the space between the front walls of the interior structure and housing.

4. A space heater as defined by claim 1, wherein in the top wall of the housing is insulated.

5. A space heater comprising the combination of elements defined by claim 1, and heat transfer fins projecting from the inner surfaces of the top and front walls of the housing, those applied to said front wall being relatively wide and located above the top plane of the combustion device.

6. An space heater comprising the combination of elements defined by claim 1, and air impelling means supported within the lower portion of the housing and arranged to move air upwardly through the space between the front walls of the interior structure and housing.

7. A space heater comprising a wide and relatively shallow from front-to-rear rectangular housing for installation on the inner side of a building wall below a window, a duct leading rearwardly from the upper portion of the housing and corresponding in width therewith and adapted to project out through the window between the window frame and sash, an interior rectangular structure enclosing a combustion chamber and setting off a circulating space separate from said chamber that opens exteriorly of the housing at top and bottom, said structure being only slightly less in horizontal cross sectional area than the housing and including a flue equal in width therewith that leads rearwardly from the top portion of the combustion chamber through the aforesaid duct in spaced relation to the surrounding walls thereof to provide a passage about the flue leading into and downwardly within the rear portion of the housing and substantially throughout the width thereof, said passage communicating with the bottom portion of the combustion chamber, and a combustion device within the combustion chamber and occupying a major portion of the horizontal across sectional area thereof.

8. A space heater comprising a wide and relatively shallow from front-to-rear rectangular housing for installation on the inner side of a building wall below a window, a duct extending rearwardly from the top portion of the housing and adapted to project out through the window between the window sill and sash, the duct extending substantially the full width of the housing and being relatively shallow in a vertical direction, the bottom of the duct being provided with an abrupt vertical shoulder adapted to overhang the outer edge of the window ledge and the top of the housing being depressed to receive the window sash, an interior rectangular structure enclosing a combustion chamber and setting off a circulating space separate from said chamber that opens exteriorly of the housing at top and bottom, said structure being only slightly less in horizontal cross sectional area than the housing and including a flue equal in width therewith that leads rearwardly from the top portion of the combustion chamber through the aforesaid duct in spaced relation to the walls thereof to provide a passage through the duct adjacent the flue leading into and downwardly within the rear portion of the housing and substantially through the width

thereof, said passage communicating with the combustion chamber adjacent the bottom of the latter, and a combustion device arranged to discharge its products into the combustion chamber.

5 9. A space heater characterized by the combination and arrangement of elements set forth in claim 7, and heat transfer fins extending inwardly and outwardly from the wall of said interior structure that separates the combustion chamber from said air circulating space.

10 10. A space heater characterized by the combination and arrangement of elements set forth in claim 7, and air impelling means situated in 15 the lower part of the housing for moving air upwardly therethrough.

11. A space heater comprising a relatively wide housing that is shallow from front to rear and that is adapted to be attached to a wall beneath

20 a window in spaced relation to the floor, a duct of substantially the same width as the housing extending rearwardly from the top portion thereof and adapted to project through the window between the window frame and sash, a casing in

25 the housing in slightly, rearwardly spaced relation to the front wall of the latter to provide a circulating space, the casing extending substantially from side to side of the housing and enclosing a combustion chamber, a flue of sub-

30 stantially the same width as the casing extending rearwardly from the top portion thereof out through the aforesaid duct and arranged therein to provide a passage about the flue for incoming air, the rear of the casing being spaced for-

35 wardly from the rear wall of the housing to provide a space into the upper end of which said passage opens and which space communicates at its lower end with the combustion chamber substantially throughout the width of the latter, the

40 housing having air inlet and air outlet openings communicating, respectively, with the lower end and upper end of the circulating space, and a combustion device consisting of an elongated burner arranged within the casing with its longer axis substantially parallel with the front

45 and rear walls of the casing.

12. A space heater characterized by the combination and arrangement of elements set forth in claim 11, and air impelling means supported within the lower portion of the housing and arranged to move air upwardly therethrough.

13. A spacer heater as defined by claim 11, wherein the top wall of the housing is insulated.
